UNITED STATES PATENT OFFICE.

HERMAN HORN, BERNARD HORN, AND PETER HORN, OF WASHITA COUNTY,
OKLAHOMA.

VALVE-GRINDING TOOL.

1,073,686.

Specification of Letters Patent. Patented Sept. 23, 1913

Application filed March 10, 1913. Serial No. 753,387.

To all whom it may concern:

Be it known that we, HERMAN HORN, BERNARD HORN, and PETER HORN, citizens of the United States, residing in the county 5 of Washita and State of Oklahoma, have invented new and useful Improvements in Valve-Grinding Tools, of which the following is a specification.

This invention relates to manually operated valve grinding tools of the portable type designed to impart an oscillating movement to the valve being ground.

The invention has for its main object to provide a tool of this nature which (a) may 10 be adjusted for light or heavy grinding, (b) will automatically adjust itself into alinement with the valve during the operation of the tool, (c) is provided with oppositely extending handles movable longitudinally of 15 the tool for operating it whereby the pressure exerted on the handles will be distributed evenly on the opposite sides of the tool and minimize the tendency of the tool to move out of alinement with the valve, 20 (d) as in prior structures of this nature, 25 is provided with a lost motion connection admitting the starting of the tool to acquire sufficient momentum before the valve is actuated, which connection insures an even 30 grinding of the valve and renders the starting of the tool at each end of its stroke comparatively easy, and (e) has an offset extended portion for use in confined places 35 where tools of this nature cannot ordinarily be used.

The above and other objects of this invention are accomplished by providing a tool having a main shaft with a cross-bar mounted at its middle portion on the shaft and to 40 slide longitudinally of the shaft, the cross-bar having handles on its outer ends and having secured thereto the opposite ends of a cord or other flexible operating member, the middle portion of which is secured to the 45 upper end of the shaft.

The turning of the shaft winds the middle portion of the cord thereabout to raise the cross-bar. Downward pressure on the opposite ends of the cross-bar draws the opposite 50 ends of the cord and rotates the shaft in an opposite direction. An expandible momen-

tum or fly wheel is secured to the shaft to insure the steady and even turning of the shaft and the winding of the cord thereabout after the downward thrust of the handle bar.

The fly wheel may be expanded to obtain a relatively slow and powerful movement of the tool when heavy grinding is to be done, and may be contracted to secure a relatively quick and less powerful movement of the tool when light grinding is to be done. The valve engaging part of the tool is attached to the shaft by a suitable connection admitting of the free turning of the shaft 60 through a predetermined period of a revolution prior to the turning of the tool, the connection admitting of this lost motion upon the turning of the shaft in either direction.

The tool is provided with an offset or angular extension which may be quickly attached to or removed from the tool, and by means of which the operations of the tool 65 may be carried on in confined places which will not accommodate or permit the operation of the tool.

Other objects and advantages of this invention will appear from the following specific disclosure of the same as set forth in the below detailed description and accompanying drawings, in which:

Figure 1 is an elevational view of the tool in operative position. Fig. 2 is a section on the line 2--2 of Fig. 1. Fig. 3 is a detail view of the momentum or fly wheel employed. Fig. 4 is a sectional view through the valve engaging tool connection. Fig. 5 is a transverse section through the same. Fig. 6 is a detail view of the extension attachment as applied to the lower end of the 70 tool. Fig. 7 is an elevational view of the outer end of the extension member showing in section the connection for the gears. Fig. 8 is a view in elevation of another form of valve engaging tool, showing the application of 75 the same to a valve.

Referring to the drawings in which like characters of reference designate similar parts throughout the several views, 10 designates a spindle arranged vertically and provided upon its upper end with an enlarged or drum portion 11 about which is

- adapted to wind the intermediate portion of a cord 12, or other flexible operating member. The intermediate portion of the cord 12 is passed up through opposite ends of a retaining plate 13, which plate fits snugly over an angular extension 14 of the spindle 10, as shown to advantage in Fig. 1. The ends of the cord 12 extend oppositely from the drum 11, and are secured to the opposite outer ends of a cross bar 15. The cross bar 15 is supported upon a T 16 slidably longitudinally upon the spindle and arranged below the drum 11. Upon the extremities of the cross bar 15 are mounted a pair of handles 17 adapted to be grasped by the operator and pressed down in a direction longitudinally of the spindle 10, whereby to unwind the cord 12 from the drum 11, and rotate the spindle 10.
- 20 In order to cause a steady and easy rotation of the spindle 10, the spindle is provided with a fly wheel. This fly wheel comprises a pair of blocks 18 arranged in spaced relation upon the spindle 10, and being adjustably clamped thereon. Secured to the opposite sides of the blocks are leaf springs 19, the ends of which are permanently attached to the corresponding sides of the blocks, the springs 19 being 30 adapted to be expanded or contracted by the movements of the blocks toward and from each other. Each spring 19 carries at its intermediate portion a weight 20, the same being preferably located against the inner side of the spring 19, and being grooved in its outer face whereby to snugly receive the intermediate portion of the spring 19 to insure the securement of the weight 20 to the spring and prevent the 35 turning of the weight. The weight 20 is secured to the spring 19 in any suitable manner, as by a rivet 21 as shown.
- 40 The lower end of the spindle 10, as best seen in Figs. 4 and 5, is provided with a groove 22 extending nearly all the way around the spindle, the portion of the spindle between the ends of the groove 22 constituting a stop 23. A sleeve 24 engages over the lower end of the spindle, and carries a stop pin 25, the same preferably comprising a set screw, as shown in the accompanying drawings. From Fig. 4 it will be noted that the set screw engages in the groove 22, and upon rotation of the spindle 50 55 60 65 70 75 80 85 90 95 100 105 110 115 120 125 130
- 10 within the sleeve through nearly a complete revolution the stop 23 engages the stop pin 25, and the sleeve 24 is thereby carried with the spindle. Within the lower end of the sleeve 24 is fitted the shank of a valve engaging tool 26, the same being disclosed in Fig. 1 as comprising a forked arm, the ends of which are reduced to engage in corresponding openings or recesses usually found in the upper faces of valves 65 of internal combustion engines.

In Fig. 8 is disclosed in elevation another form of valve engaging tool 26^a, wherein the lower end is flattened and rounded to provide a blade adapted to engage in a kerf in the upper face of the valve, as shown in 70 dotted lines in Fig. 8.

In the operation of this tool the spindle 10 is rotated by hand sufficiently to wind a portion of the cord 12 upon the drum 11, as shown in Fig. 1. The spindle 10 is inserted at its lower end into the head of a cylinder 27, and the valve engaging tool is adjusted to the valve in the engine cylinder head. The operator now moves the cross bar 15 down by pressure on the handles 17, whereby the cord 12 is drawn taut, and causes the rotation of the drum 11 and the spindle 10. This turning of the spindle 10 rotates the fly or momentum wheel, the same being fixed on the spindle 10, and the momentum of the fly wheel is sufficient to carry the spindle in its forward turning movement to rewind the cord 12 upon the drum 11, but in an opposite direction. As the cord 12 is rewound upon the drum 11, the cross bar 15 is drawn up. The operator again presses down upon the handles 17, which action unwinds the cord 12 from the drum 11, and rotates the spindle 10 in a reverse direction. Subsequent to each thrust of the cross bar 15 the fly wheel effects the continued rotation of the spindle 10 sufficient to rewind the cord 12 upon the drum in an opposite direction. Thus a reciprocating motion is imparted to the spindle and to 95 the valve which is connected to the same. At intervals during this operation the tool is removed from the valve, and a quantity of flour of emery, carborundum, or a like grinding substance is placed between the 100 valve and its seat, when the tool is replaced on the valve and the operation continued.

From Figs. 1 and 3 it will be noted that the fly wheel may be expanded or collapsed, the fly wheel being expanded when it is desired to obtain greater momentum to the tool in grinding relatively large valves, or valves offering considerable resistance. When such heavy work is not to be done with the tool, it is found more desirable to collapse 110 the fly wheel, as shown in Fig. 3, whereby a relatively quick motion and sufficient power is had for operating ordinary valves. The fly wheel is adjusted to spread the weights 115 120 125 130

20 and to draw the same together by moving the blocks 18 toward and from each other respectively.

The lost motion connection had between the valve engaging tool and the spindle admits of the starting of the spindle in its rotation in either direction before the valve is connected to the spindle, so that sufficient momentum to the tool is had to overcome any friction between the valve and its seat which might otherwise stop the tool.

In the use of tools of this nature it is frequently found that the valves are so positioned in the cylinder head, and the cylinder is so located upon the motor vehicle or other mounting for the engine that the valve tool cannot be used. To overcome this difficulty this invention provides an extension or angle portion for the tool by means of which the operations of the tool may be carried on in these confined or restricted places. In Fig. 6 of the drawings such an instance is shown, and the figure also shows the improved extension applied to a valve under such conditions. The cylinder 28 is shown as located partly beneath the dash board 29 of a motor vehicle, and in such position that the tool as disclosed in Fig. 1 can be applied to the valve. The lower end of the spindle 10 is removed from the sleeve 24 and seated in a socket plug 30, the shank of which is screwed into any available threaded opening in the upper end of the cylinder 28. The tool rises from the socket plug 30, as shown in Fig. 1, and may be operated as above described. A bracket 31 is carried by the tool and provided with spaced sleeves 32 through which the spindle 10 passes. Between the sleeves 32 is disposed a beveled gear 33 secured to the spindle 10 by a set screw or other suitable adjustable fastening means. The bracket is also provided with a bearing 34 supporting a shaft 35 upon the inner end of which is secured a second beveled gear wheel 36 meshing with the gear 33. The shaft 35 extends considerably beyond the bearing 34, and is provided with a relatively wide groove 37 extending nearly all the way around the shaft 35. The portion of the shaft 35 between the ends of the groove 37 constitutes a stop 38 adapted to strike a stop pin 39 carried upon the bored portion 40 of an outer shaft section 41. The shaft 35 projects into the bored portion 40, and is locked to the same by the stop pin 39. The outer shaft portion 41 is reduced at its end, and has such end mounted in a bearing 42 of an outer bracket 43. A beveled gear 44 is mounted upon the outer section 41 of the shaft, and bears against the outer end of the bearing 42. The bracket 43 is provided with a pair of spaced sleeves 45 through which is slidably disposed a reduced spindle 46. A second beveled gear 47 is keyed upon the reduced spindle 46 between the sleeves 45, the gear 47 meshing with the gear 44, and being mounted to slide longitudinally upon the short spindle 46. The spindle 46 is provided with any suitable valve engaging member, shown in Fig. 6 as comprising a forked arm, the ends of which are seated in depressions or recesses formed in the upper face of the valve.

For the purpose of exerting a yielding pressure upon the valve to force the same upon its seat, and to accommodate in-

equalities in the grinding and operation of the tool, the short spindle 46 is provided with tension means for holding it down against the valve. This tension means is shown in Figs. 6 and 7, whereby a lower semi-elliptic spring 48 is mounted upon the short spindle 46 at its middle portion, and is held up against the lower side of the outer sleeve 46 by a second semi-elliptic spring 49. The spring 49 has a reduced opening at its lower portion through which projects the stud 50 constituting a reduced portion of the short spindle 46, and forming a shoulder to support the spring 49. The ends of the springs 48 and 49 are connected together in any suitable manner, as by nuts and bolts, as shown at 51, whereby the springs 48 and 49 are not only connected together but are placed under the desired tension. The lower spring is held against the lower end of the sleeve 45, and tends to draw the upper spring down toward the sleeve 45. Since the spindle has a shoulder engaging the upper spring 49, the short spindle 46 is yieldingly held down upon the valve.

The operation of this extension is as follows: When the spindle 10 is rotated the gear wheel 33 is carried therewith, and rotates the gear wheel 36, turning the shaft 35. When the stop 38 on the shaft 35 is turned sufficiently to engage the stop pin 39, the shaft extension portion 41 is turned with the spindle 10. By means of the gears 44 and 47 the short spindle 46 is rotated, thus rotating the valve connected to the spindle 46. In order to support the extension portion of the tool upon the cylinder 28, a suitable bracket 52 is employed which is secured at one end by a screw bolt 53 to the top of the cylinder, which has its opposite end detachably secured to the bearing 42 by means of the winged nut 54 carried upon a threaded stud 55. The upper end of the bracket 52 is forked, the arms of which extend beneath the winged nut 54 on opposite sides of the stud 55.

What is claimed is—

1. In a valve grinding tool and in combination, a spindle, operating means for rotating the spindle, a fly wheel on the spindle for increasing the momentum thereof, a valve engaging part, and connecting means between said part and the spindle, said connecting means comprising a stop on one side of the spindle and a stop on one side of the valve engaging part, said spindle being adapted to rotate through a predetermined part of a revolution prior to the abutting of said stops.

2. In a valve grinding tool, and in combination, a spindle, means carried by the spindle for imparting a reciprocating rotary motion to the same and being movable in the direction of the length of the spindle, a

fly-wheel on the spindle adapted for adjustment to increase and decrease the momentum of the fly-wheel, a valve engaging part, and a lost-motion connection between said 5 valve engaging part and the spindle whereby the tool may be started to gain momentum prior to turning said part.

In testimony whereof we have hereunto

set our hands in presence of two subscribing witnesses.
